UNITED STATES PATENT OFFICE.

WILBERT LYON, OF CRAWFORDSVILLE, INDIANA, ASSIGNOR TO C. T. C. MFG. CO., OF INDIANAPOLIS, INDIANA, A COPARTNERSHIP CONSISTING OF A. E. CONN, C. A. THOMAS, AND G. C. CONN.

TIMER BRUSH.

Application filed September 2, 1918, Serial No. 321,217. Renewed August 25, 1922. Serial No. 584,237.

To all whom it may concern:

Be it known that I, WILBERT LYON, a citizen of the United States, residing at Crawfordsville, in the county of Montgomery and State of Indiana, have invented certain new and useful Improvements in Timer Brushes; and I do declare the following to be a full, clear, and exact description of the invention, such as will enable others skilled 10 in the art to which it appertains to make and use the same.

This invention relates to improvements in timer brushes, the same being particularly designed for use in connection with Ford 15 machines, although it is not to be restricted to such use.

The principal object of the invention is to produce a device of the above mentioned type which will overcome, as much as possible, excessive wear on the contacts and insulation of the timer shell, but at the same 20 time will make a firm wiping contact at all times.

A further object of the invention is to provide means associated with the shoe and contact brush to lubricate the path of travel of the shoe and brush, said shoe also having means associated therewith to collect any 25 surplus dirt and oil.

Another object of the invention is to provide a device of the type specified which is simple in construction, strong, durable, effective in operation, and comparatively inexpensive to manufacture.

In the accompanying drawings forming a part of this specification, and in which like numerals are employed to designate like parts throughout the same:

Fig. 1 is a perspective view of a timer 40 brush constructed in accordance with my invention, the parts being in assembled position.

Fig. 2 is a detail perspective view of the shoe.

Fig. 3 is a detail perspective of the carrier for the shoe.

Fig. 4 is a central vertical sectional view on the plane of the line 4-4 of Fig. 1.

In the drawings, wherein for the purpose 50 of illustration is shown a preferred embodiment of my invention, the numeral 1 designates a carrier or supporting member which is provided with a central sleeve or hub 2, having notches 3 therein, whereby the said 55 carrier may be readily attached to a timer

shaft by the usual means. The carrier also includes a plurality of spaced oppositely disposed supporting arms 4, through the ends of which guide pins or bearing members 5 are extended, the purpose of which 60 will hereinafter be set forth.

The brush supporting block or shoe 6 is, by preference, made of insulation material of good wearing quality, and is substantially semicircular in configuration, its size 65 being equal to approximately one-half of the entire circumference of the timer shell in which it operates. Because of the peculiar shape and size of this shoe 6, it will be seen that it will fit snugly in the shell, 70 thus serving as a substantial relative bracing means for the shell and timer shaft, and at the same time insuring a perfect wiping contact at all times and preventing excessive wear on the contact points and path 75 of the timer shell. Notches 7 are provided in the inner edge of the shoe and these notches fit loosely over the guide or bearing pins 5 in the carrier, thus permitting the shoe to move freely in a radial direction with respect to the carrier and at the same time causing rotation of the shoe 80 with the carrier. This construction also permits the shoe to be reversed whenever desired. Such reversal of the shoe will be 85 found advantageous in that it will compensate wear. It also serves another purpose, which will hereinafter be set forth. The brush block 6 is recessed at 8 to permit the arms 4 of the carrier to fit therein. The 90 shoe is provided at its center with a radial opening 11 in which a gauze contact brush 9 is seated and normally pressed out against the contact points in the timer shell by a coil spring 10 which bears on the carrier 1, said spring being held in its proper 95 position by an outwardly projecting pin 12 on the carrier 1.

To prevent dirt and gummy oils from collecting on the path of brush 9 and interfering with the proper operation thereof, I provide transverse notches or gutters 13 in the bearing surface of the shoe which serve to collect any dirt and oil, thereby protecting the brush. The notches are, by 100 preference, located on opposite sides, and close to the brush 9, or rather, the opening 11. It is to be noted that during the operation of the shoe, the dirt and oil will be 105 collected in the notch in front of the brush, 110

so, when this notch becomes full, it will be necessary to reverse the shoe to bring the other notch into effective position. I also provide sockets 14 in the shoe 6, there being 5 one on each side of the brush, and these sockets receive oil wicks 15, which wipe and oil the path of travel of the shoe, thereby preventing undue friction between the shell and shoe and between the brush and contacts.

When in working position, the shoe 6 will normally be forced in a radial direction away from the carrier member 1 and into yielding engagement with the contact 15 points and inner periphery of the timer shell by suitable means, such as a bow spring 16. This spring is extended through an ear 17 on the carrier 1, its opposite ends being received in the holes 18 adjacent the end 20 of the shoe 6 and are thus held in proper position.

By the construction disclosed, a timer is provided which is of great advantage over those employing a comparatively small 25 sweeping roller or shoe, since, even though the mounting means of the timer casing and the bearings of the timer shaft may be badly worn, relative vibration of the casing and shaft are prevented, and they are maintained 30 in proper operative relation with each other by the shoe 6 contacting with the timer casing throughout approximately half the circumference of the latter. Furthermore, the comparatively small brush 9 will itself wear, 35 rather than wear the brush path and contacts. It may easily be renewed, however, whenever necessary.

It is believed that the manner of assembling the parts, and operation of the device 40 is obvious from the foregoing description; therefore, further explanation is deemed unnecessary.

The device as described and shown has been 45 in actual use for some time and has proved to be a success, having been tested by skilled mechanics. It is so constructed that it may be readily repaired. This timer is not only effective, but is inexpensive, in that it will 50 create little or no wear on the contact points and insulation of the shell because of its yielding contact therewith.

It is to be understood that the form of my invention herein shown and described is to be taken as a preferred embodiment of the 55 same and that various changes in the shape, size, and arrangement of parts may be resorted to without departing from the spirit of the invention or the scope of the subjoined claims.

Having thus described my invention, what I claim is:

1. In a device of the class described, a carrier adapted to be mounted on a timer shaft being provided with guide means, a 65 shoe of semi-circular shape carried by and

radially slideable on said guide means the periphery of said shoe being equal to approximately one half of the internal periphery of the timer shell in which it rotates and held in contact with the shell throughout its 70 peripheral surface and a brush carried by the shoe.

2. In a device of the class described, a carrier adapted to be mounted on a timer shaft, a shoe carried by and radially movable with respect to the carrier, its periphery being adapted to contact with the inner periphery of the timer shell, a spring pressed brush on the shoe, the shoe being provided in its periphery with a notch on one side of 80 the brush serving to collect all dirt and gummy oil from the path of the brush, and means to force the shoe radially away from the carrier and into yielding engagement with the timer shell.

3. In a device of the character described, a carrier provided with a central sleeve adapted to be secured on a timer shaft, said carrier being also provided with a plurality of oppositely disposed arms, guide pins carried by said arms, a brush carrying shoe engaging said pins, whereby said parts will be rotated together, means associated with said shoe and carrier to force said shoe into yielding engagement with a timer shell, and 95 a brush carried by said shoe.

4. In a device of the class described, a carrier adapted to be mounted on a timer shaft, a shoe carried by and radially movable with respect to said carrier, a bow spring centrally connected to the carrier and having its opposite ends connected to the shoe to force the shoe radially away from the carrier and into yielding engagement with the timer shell and a brush carried by 100 the shoe.

5. In a device of the character described, a carrier adapted to be mounted on a timer shaft, a substantially semicircular shoe carried by said carrier and free to move in a 110 radial direction with respect thereto, said shoe being provided at the center of its periphery with an opening, a brush in said opening, and means coacting with the carrier and shoe for forcing the latter radially away from the carrier and into yielding engagement with a timer shell.

6. In a device of the character described, a carrier adapted to be mounted on a timer shaft, a substantially semicircular shoe carried by said carrier and free to move in a radial direction with respect thereto, said shoe being provided at the center of its periphery with an opening and transverse notches on opposite sides of said opening, a 120 brush in said opening, and means coacting with the carrier and shoe for forcing the latter radially away from the carrier and into yielding engagement with a timer shell.

7. In a device of the character described, a 125

carrier adapted to be mounted on a timer shaft, a substantially semicircular shoe carried by said carrier and free to move in a radial direction with respect thereto, said shoe being provided at the center of its periphery with an opening, a spring pressed brush in said opening, said shoe being also provided with sockets adjacent to and on opposite sides of said opening, oil wicks seated in said 10 sockets, and means coacting with the carrier and shoe for forcing the latter radially away from the carrier and into yielding engagement with a timer shell.

8. In a device of the character described, 15 a carrier adapted to be mounted on a timer shaft, a substantially semicircular shoe carried by said carrier and free to move in a radial direction with respect thereto, said shoe being provided at the center of its periphery with an opening and transverse notches on opposite sides of said opening, 20 said shoe being also provided with sockets adjacent to and beyond said transverse notches, oil wicks seated in said sockets, a brush in said opening, and means coacting 25 with the carrier and shoe for forcing the latter radially away from the carrier and into yielding engagement with a timer shell.

9. A device of the class described, comprising a carrier having a sleeve at its center to secure said carrier to a timer shaft, said carrier also including a plurality of oppositely disposed spaced arms, guide pins carried by 30 said arms adjacent the ends thereof, a shoe 35 having notches formed in its inner edge, said notches receiving said pins therein, thereby permitting the shoe to move freely with respect to the carrier, rotated therewith or reversed, a bow spring secured to the 40 carrier, the opposite ends of said spring being engageable with the inner edge of the shoe to cause the carrier and shoe to yield

with respect to each other, and a spring actuated contact brush carried by the shoe.

10. A device of the class described comprising a carrier adapted to be mounted on a timer shaft, the same being provided with transverse guide pins extending in parallelism with the timer shaft, a shoe having a curved periphery to contact the inner periphery of the shell in which it rotates, being further provided with notches receiving said guide pins, thus serving to rotate the shoe with the carrier, to permit the latter to have free radial movement and to be reversed on the pins to compensate for wear, means to force the shoe radially away from said carrier, and a brush centrally located on the periphery of the shoe.

11. A device of character described comprising a carrier to be secured on a timer shaft, a shoe carried by and radially movable with respect to the carrier, said shoe being of a size to fit snugly in the timer shell and contact approximately one-half of the inner periphery thereof, thus constituting bracing means for the shell and shaft, a spring pressed brush carried by the shoe, and means to force the latter into yielding engagement with the timer shell.

12. In a device of the class described, a carrier adapted to be mounted on a timer shaft, a relatively large shoe of semi-circular shape carried by and radially movable from said carrier, coacting means between the carrier and shoe to permit the latter to be reversed to compensate wear, and to cause it to rotate with said carrier, and a brush centrally located on the curved periphery of the shoe.

In testimony whereof I have hereunto set my hand.

WILBERT LYON.
